[57] CLAIM

The ornamental design for a bi-leaf surgical instrument handle, as shown and described.

DESCRIPTION

FIG. 1 is a top perspective view of a bi-leaf surgical instrument handle showing our new design;

FIG. 2 is a side elevation view thereof, the opposite side being a mirror image;

FIG. 3 is a top plan view thereof, the bottom being a mirror image;

FIG. 4 is a rear elevation view thereof; and,

FIG. 5 is a front elevation view thereof.

The broken lines showing a shaft is for illustrative purposes only and forms no part of the claimed design.
